TYPOGRAPHICAL DISTRIBUTING MACHINE

Louis Rossetto, Flushing, and Gino F. Squassoni,
Corona, N. Y., assignors to Mergenthaler Linotype Company, a corporation of New York

Application September 2, 1950, Serial No. 183,034

15 Claims. (Cl. 199—16)

1

This invention relates to typographical distributing machines, such as Linotype machines of the general organization represented in Letters Patent of the United States to O. Mergenthaler No. 436,532, wherein circulating matrices are released from a magazine in the order in which their characters are to appear in print and then assembled in line, the composed line transferred to the face of a slotted mold, the mold filled with molten metal to form a slug or type bar against the matrices which produce the type characters thereon, and the matrices thereafter returned through distributing mechanism to the magazine from which they started.

More particularly, it relates to machines of the multiple magazine variety, wherein the magazines are movable upwardly and downwardly in the machine frame to bring different selected magazines into operative relation to the assembling and distributing mechanisms. There are several different commercial models which make up this class of machines and the present invention has been developed particularly in connection with those models which include as features the improvements disclosed in application for U. S. Letters Patent, Serial No. 171,584, of John H. Hilpman, filed July 1, 1950.

In these machines, the shifting of the magazines is effected by a crank handle located at the front of the machine and connected to a magazine elevating mechanism which provides for a quick, easy and smooth shifting of the magazines in changing from one to another. Preparatory to shifting magazines, however, the depression of a hand lever is required to release the locking mechanism and to perform various safety functions prior to shifting magazines. Thus, for example, to avoid the dangers arising from a matrix lodged across the line of communication between a magazine entrance and a magazine at the time of shifting, the magazine entrance is adapted to be swung backwardly out of its operative position in response to the operation of the hand lever. Moreover, in order to prevent the shifting of magazines when the matrices are in the process of distribution, a matrix feeler is adapted to move into contact with any matrices in the process of distribution and, consequently, to prevent the release of the locking mechanism upon contact with any such matrices.

In accordance with the present invention, the above-mentioned and other safety features are effectuated by improved electrical means. For example, the magazine shifting mechanism is rendered inoperative, not only when matrices

2

are in the process of distribution on the distributor bar, and when a matrix becomes lodged across the gap between the magazine entrance and the magazine, but also, under certain conditions, when matrices in the course of distribution have not as yet reached the distributor bar but are still in the process of being advanced through the upper distributor box. In other words, under any of the three stated conditions, the magazine shifting mechanism is positively locked out of operation.

In addition, the present invention also provides an improved system of safety signal lamps. Other such signal systems have heretofore been proposed but generally they have involved the use of danger signals to indicate unsafe conditions. When trouble occurs in the safety system, this type of lamp usually fails to function, with the result that the operator is misled into believing that a safe condition exists. With the safety lamp system herein proposed, however, the signal system is operative only when a safe condition exists, and if the signal system goes out of order, the operator is warned of this condition by the failure to receive a safe signal.

Furthermore, the safety mechanism herein proposed normally locks the magazine shifting mechanism out of operation unless a safe condition exists, and here again, if the safety mechanism goes out of order, the operator is put on notice of this condition by the non-release of the locking mechanism, thereby preventing the shifting of magazines.

These and other improvements will be described in the detailed description following:

Referring to the drawings:

Fig. 1 is a side elevation of a Linotype machine embodying the present improvements;

Fig. 2 is a fragmentary front elevation of the distributing mechanism;

Fig. 3 is a front view of the safety lock which prevents the shifting of magazines;

Fig. 4 is an enlarged side elevation of the distributing mechanism;

Fig. 5 is a view similar to Fig. 4, but illustrating a matrix lodged across the gap between a magazine entrance and the magazine;

Fig. 6 is a view of a detail of the magazine entrance safety mechanism; and

Fig. 7 is a circuit diagram for the entire electric safety system.

In the embodiment illustrated, the present improvements have been shown as applied to a so-called "mixing" machine, equipped with four inclined magazines A¹, A², A³ and A⁴ removably

mounted on separate base frames conjointly constituting a shift frame, which is arranged to be moved upwardly and downwardly by operation of a crank handle A⁵ at the front of the machine. The magazines are selectable in pairs, instead of singly, so that matrices may be withdrawn from either magazine of the selected pair and, after the casting operation, returned by the distributing mechanism to their respective magazine channels. However, it will be obvious from the description to follow that the improvements are applicable to any multiple magazine machine of the shiftable variety.

The actual mechanism for raising and lowering the magazines is well known in the art and forms no part of the instant invention. For present purposes, it suffices to say that the operation of the crank handle A⁵, through the long fore-and-aft shaft A⁶ and the short shaft G², effects the upward and downward movement of an inclined magazine elevating slide F through counterbalanced gear mechanism denoted generally by the reference letter G.

Both operative magazines are served by a common distributing mechanism, denoted generally by the reference letter D. As well understood, the matrices, after the completion of the casting operation, are transferred onto a V-shaped second elevator bar C (Fig. 2), whereon they are lifted to the distributor box C⁵ and pushed, by means of a cam operated shifter bar C¹ and pusher member C² onto and across a stationary V-shaped bar C⁸ (Fig. 7) located in the box. Also located in the distributor box is a lifter C³ which rises at regular, evenly timed intervals, to feed the matrices therefrom, one at a time. Those matrices which are to be returned to the lower operative magazine pass onto the upper distributor bar D¹, while those matrices which are to be returned to the upper operative magazine are permitted to fall into a chute C⁷ leading to a lower distributor box C⁶, from which they are individually fed, by means of another lifter C⁴, onto the lower distributor bar D² (see Fig. 2). In either case, however, the matrices are advanced along the respective distributor bars D¹, D² by rotating screws D⁵, there being three of such screws associated with each distributor bar. After they are released from the distributor bar D¹ or D², the matrices pass through the appropriate magazine entrance D³ or D⁴ and thence into the corresponding operative magazine (A¹ or A² as in the case of Fig. 1 and A³ or A⁴ as in the case of Figs. 4 and 5), where they are stored until selectively released by the operation of the keyboard B.

As fully shown and described in the aforementioned Hilpman application, the inclined elevating slide F, which can be raised or lowered by the crank handle A⁵ to select the desired pair of magazines, is adapted to be locked in its different positions by means of a locating and locking pawl J¹ cooperating with notches F¹ formed in the rear side of the slide. There is no need herein to fully describe the operation or functions of the locking pawl J¹ except to point out that it is ordinarily maintained in its locking position by means of a spring J² but is adapted to be withdrawn from the active notch by the depression of a hand lever J preparatory to shifting magazines. In addition, the hand lever J also effects the movement of matrix guards S across the discharge ends of the two operative magazines. If the matrix guards encounter any interference from a matrix protruding from the lower end of either magazine

in use, the hand lever J cannot be operated to release the locking pawl J¹.

As heretofore explained, one of the purposes of the present invention is to prevent the shifting of magazines when the matrices are still in the process of distribution, or when a matrix becomes lodged across the gap between the magazine entrance D³ or D⁴ and the corresponding magazine. Toward this end, therefore, a notched or toothed wheel G¹ is secured to the shaft G² of the counterbalanced gear mechanism G. A pivotal pawl G³, under tension of a spring G⁴ (see Fig. 3), normally engages one of the notches of the wheel G¹, thereby preventing the operation of the hand crank A⁵ to raise or lower the magazines. The pawl G³, however, is connected to a solenoid or equivalent electrical element E¹ which, when energized, withdraws the pawl G³ from engagement with the wheel G¹ to permit the shifting of the magazines. To briefly summarize the general scheme of operation, the solenoid E¹ is generally deenergized but, when the pawl J¹ is released by the depression of the hand lever J preparatory to shifting magazines, a switch E² is thereby closed to energize the solenoid, provided the matrices have all been distributed, and provided further that the magazine entrances are clear.

The operation of the various safety features can be best understood by reference to Fig. 7, showing the electrical circuit and the various mechanical parts associated therewith. The elements of the control circuit are housed in a control box E (Fig. 1), wherein the usual source of A. C. voltage is fed into a step-up transformer 1 and tapped off in the various quantities needed. One of said tap-offs leads to the heater 3 of a thyratron control tube 2, said heater serving to bring the cathode 5 to the proper temperature to cause electron emission therefrom. When a safe condition prevails in the distributor, the thyratron conducts positive half waves of current to complete a holding circuit for a relay 4. As shown, the screen 7 and the grid 6 of the control tube are tied to the cathode, the latter being tied thereto through a time delay condenser 9 and resistor 10. The holding circuit for the relay 4 may be traced from the cathode 5, tied to ground, to the plate 8 and back to a 150 volt tap-off through the relay 4. A smoothing condenser 11 in parallel with the relay 4 serves to even out the flow of current for the holding circuit. When energized, the relay 4 serves to hold contacts 11 and 12 closed to maintain the solenoid E¹ in readiness for operation but, when the relay 4 is de-energized, the contacts are opened (as shown in Fig. 7) to prevent the energization of the solenoid E¹.

Turning for a moment to the magazine entrances D³ and D⁴, it should be evident that the magazines are adapted to be shifted with respect to the lower or discharge ends of the said entrances and, as explained above, occasionally a matrix becomes lodged in the small space between its magazine and the corresponding magazine entrance (see Fig. 6). To prevent any consequent damage when the magazines are attempted to be shifted under these conditions, the lower or discharge end of each of the magazine entrances D³ and D⁴ is provided with pivoted upper and lower extension members or flaps K¹ and K², respectively. The lower flaps K² are held in position by means of spring urged arms K³ (see especially Fig. 6), there being preferably two of said arms, one at each end, serving to hold each of said flaps

in proper position. As shown, each of the arms K^3 is pivotally connected to a small bell crank lever K^4 , itself pivotally mounted on the underside of the magazine entrance supporting frame D^6 or D^7 and serving, under the tension of a spring K^5 , to maintain the connected flap K^2 in proper position to form a bridge for the matrices between the magazine entrance and the corresponding magazine. The upper flaps K^1 are pivotally mounted on brackets D^8 connected to each of the entrance supporting frames D^6 and D^7 and are adapted to maintain their proper position by means of gravity.

Attached to the flaps K^2 at one end, so as not to interfere with the passage of matrices, are a pair of electrical switches connected in series, one switch E^4 for the upper magazine entrance and a second switch E^5 for the lower magazine entrance. These switches are of the normally open type, but are generally maintained in closed condition by the weight of the upper flaps K^1 acting on the contacts of the switches through pins K^6 depending from said flaps.

As stated above, when the distributor box C^5 and the distributor bars D^1 and D^2 are clear, the relay 4 will be energized, so that if it is desired to shift magazines, the solenoid E^1 will be energized by the closing of the switch E^2 when the operator depresses the handle J to release the locking pawl J^1 , all in the manner above described. The circuit may be traced in Fig. 7 over the 24 volt tap-off of the transformer 1 through the switches E^2 , E^4 and E^5 to the solenoid E^1 , then through the contacts 12 and 11 of the relay 4 , and back to ground. When this circuit is completed, the energization of the solenoid E^1 will effect the release of the pawl G^3 from the notched wheel G^1 and thereby permit the shifting of the magazines. If, however, a matrix is lodged in the gap between a magazine entrance and its magazine (as in Fig. 5), as soon as the magazines start to move, the matrix so lodged will force either an upper flap K^1 , in the case where an attempt is made to lower the magazines under such a condition, or a lower flap K^2 , in the case where an attempt is made to raise the magazines under such a condition, pivotally out of the way a sufficient distance (which need be very slight) to open one of the switches E^4 or E^5 , as the case may be. When one of the switches E^4 or E^5 is opened, the circuit for the energization of the solenoid E^1 is broken, and the spring actuated locking pawl G^3 is permitted to reengage one of the notches of the wheel G^1 to prevent any further operation of the shifting mechanism G .

As previously stated, the solenoid 4 is energized for operation only when the distributor box C^5 and the distributor bars D^1 and D^2 are completely free of matrices. Toward this end, a normally closed switch E^3 (Figs. 2 and 7) is arranged to be opened by the shifter bar C^1 only when the shifter bar reaches its rightmost position, indicating that all the matrices have been pushed through the distributor box C^5 by the pusher C^2 and that the distributor box, therefore, is clear of matrices. As for the distributor bars D^1 and D^2 , they are tied together by an electrical conductor and are insulated from the frame of the machine, whereas the distributor screws D^5 are grounded to the machine frame. One of the contacts of the switch E^3 is connected to ground while the other contact thereof is connected to one of the distributor bars (D^1 as in the case of Fig. 7). The distributor bar D^2 is connected to the $D.C.$ side of a rectifier 13 , which latter is connected to

a 12.6 volt tap-off of the transformer 1 ; the center tap of the 12.6 volt tap-off is connected to the grid 6 of the thyratron through a resistor 14 . It is evident, then, that a circuit will be closed between the distributor bar D^1 or D^2 and the respective distributor screws D^5 when any matrices are travelling across either of the bars in the process of distribution. Similarly, a circuit is normally closed through the switch E^3 until all of the matrices have been removed from the distributor box C^5 , at which time the shifter bar C^1 opens the switch E^3 . Whenever, however, any one of the three above-mentioned contacts is in a closed condition, a circuit is established to place a negative voltage on the grid 6 and thereby prevent the flow of current through the thyratron tube 2 necessary to complete the circuit to hold the relay 4 . In other words, whenever an unsafe condition exists in the distributor D due to the presence of matrices in the distributor box C^5 or on either of the distributor bars D^1 and D^2 , the relay 4 will be opened to prevent the energization of the solenoid E^1 and, consequently, to prevent the release of the locking pawl G^3 for the purpose of shifting magazines.

The present invention also provides a set of safety lamps L^1 and L^2 to indicate to the operator when it is safe to shift the magazines. These lamps are preferably located conspicuously at the front of the machine and, inasmuch as they indicate safe conditions, they are preferably green lights. The circuit for the lamp L^1 is from the 24 volt tap-off (actually it is shown in Fig. 7 connected to the terminal of the switch E^2 which is, in turn, connected to the 24 volt tap-off) through the lamp L^1 and through the resistor 15 to the lead connecting the contacts 11 and 12 of the relay 4 . The lamp L^1 is, therefore, normally lit when the relay 4 is energized, or, in other words, when the distributor box C^5 and the distributor bars D^1 and D^2 are clear of matrices. When, however, the matrices are in the process of distribution, the lamp goes out, indicating that it is not safe to shift magazines. The lamp L^2 , on the other hand, is connected in parallel with the contacts 11 and 12 of the relay 4 and the solenoid E^1 , or in other words, the circuit can be traced from ground through the resistor 16 to the lamp L^2 and back through the switches E^5 , E^4 and E^3 to the 24 volt tap-off. The lamp L^2 will ordinarily light when the switch E^2 is closed by the depression of the hand lever J but, if either of the switches E^4 and E^5 is opened by a matrix lodged between a magazine entrance and its magazine, the lamp will thereupon be extinguished as an indication of the unsafe condition. Inasmuch as the wheel G^1 will also be locked out of operation by the pawl G^3 , the operator will be able to ascertain the cause immediately when he sees that the lamp L^2 has been extinguished.

It has already been pointed out that the signal system functions to indicate safe, rather than unsafe, conditions. The advantage of such a system lies in the fact that if any of the apparatus should be faulty the operator will not be misled by mistaking the lack of a warning to indicate a safe condition. Moreover, meaningless flicker of the lamps is avoided since it is not necessary to depend on the traveling matrices to establish the lamp circuits to indicate unsafe or danger signals. Similarly, the thyratron tube 2 is operative only during safe periods, so that if the tube should blow or be otherwise faulty, the operator will be immediately put on notice when he fails to receive a safe signal.

The present invention has been shown and described as especially applicable to a mixer machine, but it should be noted that it is applicable as well to non-mixing machines. Also, the various safety features have been shown and described as applied to machines having only a bank of main magazines, but, of course, they could be likewise applied to machines having a bank of auxiliary magazines.

Also, it is evident that the present invention is not to be limited in any way by the voltages specified, or the type of current employed. Indeed, the invention has been shown and described merely in preferred form, and obviously many variations and modifications may be made therein and in its mode of application which will still be comprised within its spirit. It is to be understood, therefore, that the invention is not limited to any specific form or embodiment, except insofar as such limitations are specified in the appended claims.

What is claimed is:

1. In a typographical distributing machine equipped with a series of matrix magazines, a shift frame therefor movable upwardly and downwardly to bring a selected magazine into use, a distributor box, a distributor bar, a shifter for advancing the matrices through the distributor box to the distributor bar, a magazine entrance for guiding the matrices released from the distributor bar into the selected magazine, and a lock for preventing the operation of the shift frame, the combination therewith of an electrically controlled element for releasing said lock, an electric circuit for energizing said element, a relay for conditioning said circuit for operation, a thyratron controlled holding circuit for said relay, and means responsive to the presence of a matrix on the distributor bar for controlling the firing of the thyratron to deactivate the relay and thus prevent the energization of the lock releasing element.

2. The combination according to claim 1, including an electrical switch actuated by the shifter for controlling the firing of the thyratron.

3. The combination according to claim 1, including means actuated by the movement of the shift frame for breaking said energizing circuit when the shift frame is operated with a matrix lodged across the gap between the magazine entrance and the magazine.

4. The combination according to claim 1, including a normally lighted electric signal lamp located in the relay circuit and adapted to be extinguished by the deactivation of said circuit.

5. In a typographical distributing machine equipped with a series of matrix magazines, a shift frame therefor movable upwardly and downwardly to bring a selected magazine into use, a matrix feeler arranged to move across the discharge end of the selected magazine in the absence of protruding matrices, a distributor box, a distributor bar, a shifter for advancing the matrices through the distributor box to the distributor bar, a magazine entrance for guiding the matrices released from the distributor bar into the selected magazine, a lock engageable with a part of the magazine shift frame to locate and hold said frame in its different positions, a second lock normally operative to prevent the operation of the shift frame, manual means for operating the matrix feeler and for concurrently releasing the first lock, and electric circuit means controlled by the release of the first lock to release the second lock, said circuit means being

operative only when the distributor bar is clear of matrices.

6. The combination according to claim 5, wherein said circuit means include devices which render it operative only when the distributor box is clear of matrices.

7. In a typographical distributing machine, the combination of a series of matrix magazines, a shift frame therefor movable upwardly and downwardly to bring a selected magazine into use, manually controlled mechanism for operating said shift frame, means for locking said manually controlled mechanism out of operation, an electrically controlled element for releasing said locking means, a magazine entrance for conducting matrices in the course of distribution into the selected magazine, upper and lower flaps pivotally mounted at the discharge end of said magazine entrance, said flaps being caused to pivot when the magazines are shifted by engagement with a matrix lodged in the gap between the magazine entrance and the magazine, and an electrical switch controlled by the pivoting of either of said flaps for preventing the release of the locking means.

8. The combination according to claim 7 wherein the mounting for the upper pivotal flap allows it to be maintained in position by gravity, and including a spring to maintain the lower pivotal flap in position by spring pressure.

9. The combination according to claim 7 including an electric signal lamp controlled by said switch and operable to indicate the absence of a matrix from said gap.

10. In a typographical distributing machine, the combination of a series of matrix magazines, a shift frame therefor movable upwardly and downwardly to bring a selected magazine into use, a distributor box, a distributor bar, a shifter for advancing the matrices through the distributor box to the distributor bar, a plurality of rotating screws for moving the matrices along the distributor bar, a magazine entrance for guiding the matrices released from the distributor bar into the selected magazine, a lock for preventing the operation of said shift frame, an electrically controlled element operable to release said lock, a first electric circuit for operating said element, manually controlled means operable prior to the movement of the shift frame for closing said first circuit, a second electric circuit for conditioning said first-mentioned circuit for operation, a switch operated by said shifter for controlling said second-mentioned circuit, means controlled by matrices in the course of distribution on the distributor bar for also controlling said second-mentioned circuit, and means actuated by the movement of the shift frame for breaking said first-mentioned circuit when the shift frame is operated with a matrix lodged in the gap between the magazine entrance and the magazine.

11. In a typographical distributing machine equipped with a distributor box, a distributor bar, a shifter for advancing the matrices through the distributor box to the distributor bar, magazine shifting mechanism, and a lock for preventing the operation of said magazine shifting mechanism, the combination therewith of manually operable means for releasing said lock, an electric signal lamp automatically lighted and extinguished by the absence and presence of matrices on the distributor bar, respectively, and electric circuit means for said lamp, said circuit means including a switch which is manually actu-

ated by the lock releasing means to close the lamp circuit, and an automatic switch actuated in response to matrices on the bar to open the lamp circuit.

12. In a typographical distributing machine equipped with a distributor box, a distributor bar, a shifter for advancing the matrices through the distributor box to the distributor bar, magazine shifting mechanism, and a lock for preventing the operation of said magazine shifting mechanism, the combination therewith of manually operable means for releasing said lock, an electric signal lamp automatically lighted and extinguished by the absence and presence of matrices in the distributor box, respectively, and electric circuit means for said lamp, said circuit means including a switch which is manually actuated by the lock releasing means to close the lamp circuit, and an automatic switch actuated in response to matrices in the box to open the lamp circuit.

13. In a typographical distributing machine, the combination of a series of matrix magazines, a shift frame therefor movable upwardly and downwardly to bring a selected magazine into use, mechanism for operating said shift frame, a magazine entrance for conducting matrices in the course of distribution into the selected magazine, said entrance being provided at its discharge end with a yielding flap or section which is caused to yield during the movement of the shift frame by engagement with a matrix lodged between the magazine entrance and the selected magazine, and a lock for preventing the operation of said magazine shifting mechanism, the combination therewith of manually operable means for releasing said lock, an electric signal lamp automatically lighted and extinguished by the absence and presence of matrices lodged between the magazine and magazine entrance, respectively, and electric circuit means for said lamp, said circuit means including a switch which is manually actuated by the lock releasing means to close the lamp circuit, and an automatic switch actuated in response to matrices lodged between

40
45

the magazine and magazine entrance to open the lamp circuit.

14. In a typographical distributing machine, the combination of a series of matrix magazines, 5 a shift frame therefor movable upwardly and downwardly to bring a selected magazine into use, mechanism for operating said shift frame, a magazine entrance for conducting matrices in the course of distribution into the selected magazine, said entrance being provided at its discharge end with a yielding flap or section which is caused to yield during the movement of the shift frame by engagement with a matrix lodged between the magazine entrance and the selected magazine, a lock to arrest the movement of the shift frame, and automatic actuating means for the lock, said means being activated by the yielding of the magazine entrance flap.

15. In a typographical distributing machine, 20 the combination of a series of matrix magazines, a shift frame therefor movable upwardly and downwardly to bring a selected magazine into use, mechanism for operating said shift frame, a magazine entrance for conducting matrices in the course of distribution into the selected magazine, said entrance being provided at its discharge end with a yielding flap or section which is caused to yield during the movement of the shift frame by engagement with a matrix lodged between the 25 magazine entrance and the selected magazine, a lock to arrest the movement of the shift frame, an automatic electrical element for actuating the lock, and an electric circuit for said element, said electric circuit being activated by the yielding of 30 the magazine entrance flap.
